a corporation of New York

Application April 18, 1952, Serial No. 19,379

Term of patent 14 years

(Cl. D80—9)

To all whom it may concern:

Be it known that I, Leonard Peyser, a citizen of the United States of America, residing at White Plains, in the county of Westchester and State of New York, have invented a new, original, and ornamental Design for an Umbrella Display Stand, of which the following is a specification, reference being had to the accompanying drawing, forming part thereof.

In the drawing:

The single figure is a perspective view of the umbrella display stand, embodying my new design.

The broken lines are shown for illustrative purposes only.

I claim:

The ornamental design for an umbrella display stand, substantially as shown and described.

LEONARD PEYSER.
